Charles C. Tice Atty.

UNITED STATES PATENT OFFICE.

JOHN B. GLOWACKI, OF CHICAGO, ILLINOIS.

CARTRIDGE-FUSE FERRULE TYPE FOR REMOVABLE FUSE ELEMENTS.

Application filed February 1, 1922. Serial No. 533,194.

To all whom it may concern:

Be it known that I, JOHN B. GLOWACKI, a citizen of the Republic of Poland, having declared my intention of becoming a citizen of the United States, and a resident of the city of Chicago, in the county of Cook and State of Illinois, have invented certain new and useful Improvements in Cartridge-Fuse Ferrule Type for Removable Fuse Elements; and I do hereby declare that the following is a full, clear, and exact description of the same, reference being had to the accompanying drawings, and to the numerals of reference marked thereon, which form a part of this specification.

This invention relates to that class of fusible circuit breakers which are enclosed in cartridges.

It is an object of this invention to prepare a cartridge of the sort just mentioned in which the fusible element will be held in place by means that can be disassembled without the use of tools so that a new fusible element may be quickly inserted.

It is a further object of this invention to supply a cylinder of fibre or other compressible material with metallic thimbles which shall be secured in each end thereof.

It is a further object of this invention to so design these thimbles that the manufacture of the cartridge will not be expensive.

It is a further object of this invention to provide a vent through which the explosive force of the fuse may be relieved without danger of flame emerging from the cartridge.

Other and further important objects of this invention will be apparent from the disclosures in the drawings and specification.

The invention (in a preferred form) is illustrated on the drawings and hereinafter more fully described.

On the drawings:

Figure 1 is a side elevation of the cartridge embodying my invention mounted in clips.

Figure 2 is a view of the cartridge itself.

Figure 3 is a longitudinal section.

Figure 4 is an end view of the cartridge mounted in its clips.

Figure 5 is a longitudinal section of the cartridge on an enlarged scale taken in a plane at right angles to that in Figure 3.

Figure 6 is an end view of the cartridge with the cap and fusible element removed.

Figure 7 is a similar view with the fusible element in place.

Figure 8 is a section upon the line 8-8 of Figure 5.

Figure 9 is an edge view of the fusible element.

Figure 10 is a plan view thereof.

Figure 11 is a longitudinal section through a modified form of cartridge.

Figure 12 is an external view of a modified form of cartridge.

Figure 13 is a plan view of a washer used with this invention.

As shown on the drawings:

The cartridge is mounted in clips 1 which are secured to a base 2. The clips surround the ends of the cartridge, as shown in Figure 4, and are supplied with ears 3 to contact with the end faces of the cartridge.

The cartridge consists of a cylindrical body 4 preferably of fibre or other material which is non-conducting both for heat and for electricity and which preferably is compressible. Each end of the cylinder is supplied with a thimble 5 and 6 respectively. One of these thimbles 6 is slotted, as shown at 7 in Figure 5, to provide tongues which in the manufacture of the cartridge are bent, forcing them into the body of the fibre as shown at 8 in Figure 5. Preferably these tongues are forced into the body of the cartridge by inserting a tool through the opposite end of the cartridge before the thimble 5 is in place. The thimble 5 is secured in place by having dents 9 made in its inner surface so that the struck-up metal penetrates the body of the fibre. Said thimbles 5 and 6 may also be secured in position by screwing and riveting if desired.

Each of the thimbles is provided with a flange 10 which contacts with the edge of the fibre cylinder. Upstanding from the flange 10 is a wall 11 which may be seen in Figure 6 and is shown in dotted lines in Figure 5. At two points the wall 11 is cut away to form notches 12 and the outside of the wall 11 and of the flange 10 is threaded to receive a cap 13.

Between the cap 13 and the thimble 10 is a cover plate 14 which has two ears 15 projecting into the two notches 12. Each of the covers also has a slot 16 extending diametrically nearly across the cover. By means of the lugs 15 and notches 12, these slots are brought into parallel relation when the covers are in place. At the center of each slot 16 is an enlargement 36.

A washer is positioned against the outer

face of the cover plate 14 and extends as far as the outer edge of the wall 11. At its center it has a hole 38 which registers with the enlargement 36. An upstanding annular flange 39 provides a space 40 between the central part of the washer and the cap 13. This cap is provided with a plurality of holes 41 communicating with this space.

The fusible element 17 consists of a strip 10 of fusible conducting material having notches 18 to make narrow connecting necks 19 so that the points at which fusion will take place are definitely located. One end 15 of the element is bent through a right angle and the other end 21 is bent through a small angle before the element is inserted in the cartridge.

The cover 14 is inserted in the wall 11 and is placed with the lugs 15 in the notches 20 12. The end 21 of the element 17 is then introduced into the slot 16, and passed there-through until the bent end 20 engages the cover 14.

The washer 37 has been previously permanently attached in the cap 13 with the flange 39 away from the mouth of the cap. The cap 13 subsequent to such attachment is screwed on and retains the cover 14 in place. At the same time, this cap, by causing the 30 washer 37 to press the end 20 between the washer and the cover 14, insures good electrical contact between the cap and the fusible element. The second cover 14 is then engaged over the fusible element 17 by introducing the end 21 into the slot 16. The end 21 is then bent against the outside of the cover 14 and the cap 13 with its washer 37 in place is screwed down. This presses the end 21 against the cover 14 and insures good 40 electrical contact between this cap and the fusible element.

The caps 13 may if desired be provided with a knurled surface 22 in order to facilitate the screwing and unscrewing thereof. 45 Preferably also, the cylinder 4 is made somewhat smaller at its ends to provide shoulders 23 so that the outer surface of the caps and the main body of the cylinder will be flush.

In the modification shown in Figure 11, 50 one thimble, for example the thimble 5^a, is provided with a bar 24 extending across it and having a slot 25 therein. Preferably the slot 25 will have an enlargement at its center like the enlargement 36 in the slot 16. 55 This slotted bar takes the place of the cover 14 and the end 20 of the fusible element 17 rests against the outside of this bar and is held against it by the washer 37 in the way already described. At the other end of the 60 cartridge, the thimble 6 is provided with the notches 12 to position a cover 14 as in the modification already described.

In assembling this form of cartridge, the 65 fusible element 17 is introduced through the slot 25 until the end 20 contacts with the

bar 24. The cap 13^a with a washer 37 there-in is then screwed down and presses the end 20 against the bar 24 securing the fusible element 17 and affording good electrical contact. Then the cover 14 is placed over the 70 end 21 by introducing this end through the slot 16, the lugs on the washer being placed in the notches 12. The second cap 13^a is screwed onto this end of the cartridge and its washer 37 presses the end 21 against the 75 cover 14 as has already been described.

In the modification shown in Figure 12, the cartridge 4 has the same interior construction as the modifications already described and the caps 13^a are similar to those 80 already described except that from the outer surface of each cap projects a screw threaded stud 26 upon which is mounted a nut 27. The removal of this nut from the stud 26 is prevented by providing an enlargement 28 85 upon the end of the stud. To insure that the nut 27 shall never contact with the cap 13^a so as to close the holes 41 a washer 42 is provided, the diameter of which is small enough to insure that it will not cover the 90 holes 41.

The outer surface of the washer 42 and the inner surface of the nut 27 make a clamping bar which can serve to hold the end of a conductor so that this form of fuse 95 is particularly adapted for use with flexible conductors as in some forms of telephone switchboard work.

In the use of the device, a fusible element is inserted in the way which has been described and the cartridge is forced into the 100 clips 1 which are the terminals of the circuit to be protected by the fuse. When too large a current has blown the fuse, the cartridge is removed from the clips, the caps 13^a unscrewed and the remains of the fuse removed through the slots 16 or the slots 25 and 16. A new fusible element is then introduced in the way already described and the cartridge replaced in the clips. The use 110 of the form illustrated in Figure 12 is similar except that instead of the clips, the binding posts made by the studs 26 and nuts 27 serve for connections to the conductors.

When the fuse blows the vapors or the 115 flame, if a flame is produced, emerge through the openings 16, 36 and 38 into the space 40. There they spread out into a thin sheet and finally get to the external air through holes 41. By the time they reach the atmosphere 120 therefore their velocity has been absorbed and their heat expended so that no harmful effects can be produced thereby. The comparatively large volume of the space 40 assists materially in checking the velocity of 125 the flame or vapors and its thinness aids in cooling them. The right angle turns that they must make also helps to reduce the violence of their exit.

I am aware that numerous details of con- 130

struction may be varied through a wide range without departing from the principles of this invention, and I therefore do not purpose limiting the patent granted otherwise than necessitated by the prior art.

I claim as my invention:

1. In a fuse cartridge, a cylindrical housing of compressible material, thimbles, one in each end of said housing, each of said thimbles having a portion of its wall displaced so that it penetrates into the material of the housing from the interior thereof, the displaced portions of one only of said thimbles extending to the edge of the thimble.
- 15 2. In a fuse cartridge, a housing tube,

thimbles inserted therein, apertured means outside said thimbles holding a fuse link, apertured flanged washers bearing against the ends of said fuse link and caps having a plurality of apertures adapted to form in 20 connection with said flanged washers a plurality of circuitous vent passages leading from the interior of the housing.

In testimony whereof I have hereunto subscribed my name in the presence of two 25 subscribing witnesses.

JOHN B. GLOWACKI.
